(57) **CLAIM**

The ornamental design for a macerator pump, as shown and described.

DESCRIPTION

FIG. 1 is a perspective view of the macerator pump showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 1;

FIG. 11 is an enlarged view of a portion indicated with numeric 11 in FIG. 1;

FIG. 12 is an enlarged view of a portion indicated with numeric 12 in FIG. 1; and,

FIG. 13 is an enlarged view of a portion indicated with numeric 13 in FIG. 2.

The broken lines shown in the drawings represent portions of the macerator pump that form no part of the claimed design. The dash-dot lines in FIGS. 1, 2, 9, 10, 11, 12 and 13 represent the boundary of the enlarged portion and form no part of the claimed design.
